(57) **CLAIM**

I claim the ornamental design for fret board mounts, as shown and described.

DESCRIPTION

FIG. 1 is a perspective view of fret board mounts, showing my new design as adhered to a fret board;

FIG. 2 is an alternate perspective view thereof, illustrated without the fret board;

FIG. 3 is a top plan view of FIG. 2, the bottom plan view being a mirror image thereof;

FIG. 4 is a left-side elevational view of FIG. 2, the right-side elevational view being a mirror image thereof;

FIG. 5 is a front elevational view one of the fret board risers, taken generally along lines 5-5 of FIG. 1;

FIG. 6 is a front elevational view of a first fret board riser, taken generally along lines 6-6 of FIG. 1;

FIG. 7 is a perspective view of a second embodiment of the design;

FIG. 8 is a top plan view of FIG. 7;

FIG. 9 is a bottom plan view of FIG. 7;

FIG. 10 is a left-side elevational view of FIG. 7, the right-side elevational view being a mirror image thereof;

FIG. 11 is a front elevational view one of the fret board risers, taken generally along lines 11-11 of FIG. 7; and,

FIG. 12 is a front elevational view of a first fret board riser, taken generally along lines 12-12 of FIG. 7.

The broken lines showing of a guitar neck and fret board in FIG. 1 are included for the purpose of illustrating the invention in use, and form no part of the claimed design.
